UNITED STATES PATENT OFFICE.

JOHN GALKA, OF LEAVENWORTH, KANSAS.

SHOEMAKER'S JACK.

1,370,205.

Specification of Letters Patent.

Patented Mar. 1, 1921.

Application filed October 1, 1920. Serial No. 414,022.

To all whom it may concern:

Be it known that I, JOHN GALKA, a citizen of Poland, residing at Leavenworth, in the county of Leavenworth and State of Kansas, have invented certain new and useful Improvements in Shoemakers' Jacks, of which the following is a specification.

This invention relates to certain new and useful improvements in shoemakers' jacks and has particular reference to a lasting stand wherein the shoe last is locked in position on the post of the lasting stand to be securely retained in position against accidental displacement.

15 A further object of the invention resides in the provision of a shoemaker's jack lasting stand wherein manually operable latch devices are carried by the post of the jack for interlocking engagement with the shoe 20 to secure the same in position, the locking device being manually operable to permit the removal of the shoe last.

With the above general objects in view and others that will appear as the nature of 25 the invention is better understood, the same consists in the novel form, combination and arrangement of parts hereinafter more fully described, shown in connection with the accompanying drawing and claimed.

30 In the drawing, wherein like reference characters indicate corresponding parts throughout the several views,

Figure 1 is a fragmentary side elevational view of a shoemaker's jack constructed in 35 accordance with the present invention, there being illustrated a curved jack post mounted upon a part of a shoe machine,

Fig. 2 is a fragmentary side elevational view, partly in section of the post head and 40 shoe last positioned thereon,

Fig. 3 is a vertical sectional view taken on line III—III of Fig. 1 showing the tensioned latch devices for retaining the shoe last on the post,

45 Fig. 4 is a horizontal sectional view taken on line IV—IV of Fig. 2 showing the latch heads of the tension latch devices engaging the shank of the shoe last,

Fig. 5 is a horizontal sectional view taken 50 on line V—V of Fig. 2 showing the resilient mounting of the latch device in the jack stand, and

Fig. 6 is a side elevational view of a modified form of the invention showing a jack 55 post independent of the machine construc-

tion with the last retaining latches carried by the head thereof.

Referring more in detail to the accompanying drawing, and particularly Figs. 1 and 5, showing the preferred form of the invention the reference numeral 1 designates a machine construction upon which a curved jack post 2 is mounted and secured in position thereon by the fastening device 3. The post 2 is reinforced by lateral rods 4 and is 65 provided upon the upper end thereof with a head 5 supporting the shoe last 6 removably positioned thereon.

In order to provide a lock or latching device for retaining the last 6 upon the post 70 head 5, the post head being of increased cross sectional area as indicated in Figs. 2 and 3 is provided with an upper extension 7 into which oppositely disposed vertical 75 grooves 8 formed in the head 5 extend while the upper end of the extension 7 is provided with a transverse slot 9 communicating with the vertical slot 8, the slots 8 at each side of the head 5 and extension 7 being laterally offset relative to each other and opening at 80 the adjacent sides of the head and extension as shown in Figs. 2 and 3. A latch lever 10 is disposed in each groove 8 and is pivotally mounted on the transversely extending pin 11 and carries a beveled latch 85 head 12 at the upper end thereof extending through the transverse groove 9 and projecting laterally thereof as shown in Figs. 3 and 4. The lower end of the latch lever 10 carries an outwardly directed right angular 90 operating handle or arm 13 projecting beyond the body portion of the head 5 for engagement by the operator in shifting the latch lever 10. As shown in Fig. 3 the inner wall of the slot 8 in the head 5 is inclined as 95 at 8' to provide for an inward swinging movement of the lower end of the latch lever 10 against the tension of the spring 14 engaging the inner face of the latch lever at one of its ends with the other end thereof 100 received in the socket 5' formed in the head 5 and communicating with the slot 8. The rear wall of the slot 8 in the head extension 7 is formed perpendicular and forms an abutment stop for the outer end of the latch 105 lever.

As shown in Figs. 2 and 3 the shoe last 6 carries a mounting shank 15 having a socket 110 therein received on the head extension 7 while the inner face of the shank socket ad-

jacent the latch heads 12 is provided with keeper sockets 15' for the reception of the beveled ends of the latch heads 12.

In the operation of the device, assuming that the last 6 is displaced from the stand post 2 the beveled ends of the latch heads 12 extend laterally of the head extension 7 and by placing the shank 15 of the last 6 the latch heads 12 are moved inwardly by the engaging walls of the last shank to shift the latch levers 10 on the pivots 11 against the tension of the springs 14, and when the last has been moved home to the position shown in Fig. 3 the latch heads 12 under influence of the springs 14 will move into keeper sockets 15' therefor. Should it be desired to remove the last for purposes of placing upon the stand a different sized one, the handles 13 at opposite sides of the stand head 5 are moved inwardly against the tension of the springs 14 to shift the latch levers 10 on their pivots to displace the latch heads from engagement with the shank of the last, at which time, the last is freely slidably removable therefrom. A fastening strap 16 is carried by the machine frame 1 for engagement with a shoe placed on the last 6 and may be adjusted by the buckle connection 16' of the strap for rigidly holding the shoe positioned.

A modified form of the invention is shown in Fig. 6 wherein the last post 2' is constructed independently of a machine mounting for positioning on the floor or other support, the same being provided upon its upper end with a head 17 having an extension 18 with

the latch devices 10' carried thereby for engagement with the last in the manner described in connection with the preferred form of the invention.

40

It is not intended to limit this invention to any particular mounting for the post of the lasting jack, as the novelty strictly resides in the construction of the post head and the latch device associated therewith for retaining a shoe last in position thereon, and while there are herein shown and described the preferred embodiments of the present invention, it is nevertheless to be understood that minor changes may be made therein without departing from the spirit and scope of the invention as claimed.

45

50

What is claimed as new is:—

A lasting jack comprising a post, a head carried thereby, an extension carried by said head, said head and extension having laterally offset slots formed in opposite walls thereof and opening at the opposite sides of the head, tensioned latch levers pivotally mounted in the post head, operating handles for the latch levers extending laterally of the post head, latch heads carried by said levers extending laterally of the head extension, and a last mounted on said head extension and having keeper sockets therein for the latch heads.
